UNITED STATES PATENT OFFICE.

JESSE W. FOSTERLING, OF MISSOULA, MONTANA.

WOODWORKING-MACHINE.

1,136,594.

Specification of Letters Patent. Patented Apr. 20, 1915.

Application filed June 20, 1914. Serial No. 846,353.

To all whom it may concern:

Be it known that I, JESSE W. FOSTERLING, a citizen of the United States, residing at Missoula, in the county of Missoula and 5 State of Montana, have invented certain new and useful Improvements in Woodworking-Machines, of which the following is a specification, reference being had to the accompanying drawings.

0 This invention relates to certain improvements in wood working machines, and more particularly to jointers, the primary object of the invention residing in the provision of improved means for mounting and 15 adjusting the abrasive block or blocks with respect to the jointer head of the machine, whereby the same may be advantageously employed in connection with jointers for flooring, silo materials, wooden culverts, and 20 the like.

The invention has for a further object to produce a jointer which is so constructed that the various adjustments may be easily quickly, and accurately made, and the parts 25 will retain their adjusted or set positions and not be displaced by the vibration of the machine.

The invention has for still another object to produce a jointer for wood working machines which is simple and durable in its 30 construction, highly reliable and efficient in practical use and capable of manufacture at comparatively small cost.

With the above and other objects in view, 35 the invention consists in novel features of construction, combination, and arrangement of parts as will be hereinafter referred to and more particularly pointed out in the specification and claims.

40 For a full understanding of the invention, reference is to be had to the following description and accompanying drawings, in which—

Figure 1 is a side elevation illustrating 45 my invention in its preferred embodiment applied to use; Fig. 2 is a top plan view; Fig. 3 is an end elevation; Fig. 4 is a section taken on the line 4—4 of Fig. 3; and Fig. 5 is a section taken on the line 5—5 of 50 Fig. 2, and Fig. 6 is a section taken on the line 6—6 of Fig. 2.

Referring in detail to the drawings, 55 designates what is commonly known in the art as the chip breaker plate of a wood working machine, and 6 indicates the jointer head. In the plate or base 5, a dove tail

groove or channel 7 is formed, though it is to be understood that my invention is not to be limited to any particular manner of mounting the device itself in position with 60 respect to the jointer head.

The slide base 9 of my improved jointer is movably mounted in the groove or channel 7, and is adapted to be rigidly held against longitudinal shifting movement in 65 said channel by a clamping bolt 10 which is disposed through an opening in the plate 5, and has threaded engagement in the base 9. Upon the base plate 9 a bar 11 is mounted for longitudinal sliding movement, said bar 70 11 being provided with oppositely beveled or inclined flanges 12 for engagement with the under-cut beveled side walls 13 of the groove or channel provided in the upper surface of the base 9, upon which the bar 11 is mounted. Upon one end of the bar 11 an upstanding lug 14 is formed, and this lug is provided with a threaded opening to receive a threaded adjusting rod 15 which is rotatably mounted in a bearing standard 16 fixed 75 upon one end of the base 9. A suitable crank 17 is secured to one end of the rod 15 whereby the same may be turned. The other end of the bar 11 is increased in width and formed with spaced ears 18. The corresponding end of the base plate 9 is cut away 80 to permit of the free turning or pivotal movement of the lower end of an adjustable block carrying frame indicated generally by the numeral 19. This frame consists of the 85 parallel side bars 20 which are rigidly secured at one of their ends upon the opposite sides of the spacing block 21. A bolt 22 connects the ears 18 and upon said bolt and between the ears, the ends of the bars and the spacing block are loosely mounted. The other ends of the side bars 20 of this frame 90 are connected by the metal plate 23. Each of the bars 20 is provided upon its inner face and adjacent one of its longitudinal edges 100 with a guide channel or groove 24 having a beveled or inclined wall for engagement with the correspondingly inclined flanges 25 of the slide block 26 which is mounted for longitudinal adjustment upon the pivoted 105 frame 19. This block is provided at its upper end with an extension or lug 27 having a threaded opening to receive an adjusting rod 28 which is disposed between the side bars 20 of the frame and is rotatably 110 mounted at its upper end in the connecting plate 23.

29 designates a suitable crank handle with which the upper end of the adjusting rod is equipped, whereby the same may be readily turned and the slide block thus shifted upon the frame. This slide block is preferably formed with provision for two blocks 30 of suitable abrasive material. These blocks are securely clamped in position in the slide by the longitudinally extending plate 31 which

5 10 is arranged upon one side of the block receiving openings or recesses and rigidly secured to the slide by screws or bolts indicated at 32.

33 designates a graduated quadrant which 15 consists of two spaced curved metal bars integrally connected together at one of their ends by the U-shaped yoke 34, the arms of which are engaged in the outer faces of the respective frame bars 20 and pivotally connected thereto by the bolts 35. Upon the slide bar 11, the lower end of an arm 36 is fixed, said arm having an opening to receive the adjusting screw 15. The upper portion of this arm is obliquely inclined and 20 terminates in a threaded bolt or shank 37 which is disposed between the spaced bars of the quadrant 33. A washer 38 is engaged upon the bolt or shank 37 and provided with lugs 39 extending upon the outer sides of 25 the spaced quadrant bars. A nut 40 is threaded upon the shank 37 whereby the quadrant may be securely clamped against movement with respect to the inclined arm 36 between the washer plate 38 and the shoulders 36' on said arm. The upper surface of one of the spaced bars of the quadrant is accurately graduated in degrees, as 30 shown at 41, and upon the arm 36 an index member 42 is secured, said member projecting upwardly between the spaced bars of the quadrant as shown.

In the use of the device, the adjusting screw 15 is turned to slide the bar and dispose the abrasive blocks 30 in contiguous 45 relation to the knives on the jointer head 6. These blocks are then properly adjusted by rotating the threaded rod 28 so that the knives will engage with the blocks in the rotation of the jointer head. The frame 19 in which said blocks are carried is then disposed at the proper pitch or angle by adjusting the quadrant 33 upon the upper end of the inclined arm 36 in the manner above stated. By providing these several adjustments, the device may be employed for jointing wide knives which are set straight upon the jointer head, or beveled edge knives set at an angle upon the head. The device may 50 also be effectually used in jointing heads to be employed upon a flooring having either a square or angle joint, or silo material which is usually cut in circular form. The several adjustments may be very easily and quickly effected and the jointing operation 55 greatly facilitated.

Owing to the extreme simplicity of my invention, it will be obvious that the device can be produced at very small manufacturing cost, and the same is also durable as well as highly serviceable and convenient in practical use.

While I have above described the preferred form, construction, and arrangement of the several elements employed, it will be understood that the device is, nevertheless, susceptible of considerable modification therein, and I therefore reserve the privilege of resorting to all such legitimate changes as may be fairly embodied within the spirit and scope of the invention as claimed.

What is claimed is:

1. In a jointer for wood working machines, a base, a slide member longitudinally adjustable upon said base, a frame pivotally mounted upon said member, abrasive means longitudinally movable in said frame, means for adjusting said abrasive means in the frame, and means for securing said frame upon the slide member in various adjusted positions.

2. In a jointer for wood working machines, a base, a slide member longitudinally adjustable upon the base, means for adjusting said slide member, a frame pivotally mounted upon one end of said member, a slide block mounted upon said frame, abrasive means carried by said slide block, means for adjusting said block with respect to the frame, and means mounted upon said slide member for securing said frame in its adjusted position against pivotal movement.

3. In a jointer for wood working machines, a base, a slide member longitudinally adjustable on said base, means for adjusting the slide member, a frame pivotally mounted upon one end of said slide member, abrasive means mounted in said frame, means mounted in the frame for adjusting said abrasive means thereon, a quadrant pivotally connected at one of its ends to said frame, and means mounted upon the slide member and coöperating with said quadrant to secure the frame in its adjusted position against pivotal movement.

4. In a jointer for wood working machines, a base, a bar longitudinally adjustable upon said base, means for adjusting said bar, a frame pivotally mounted upon one end of said bar, abrasive means longitudinally adjustable upon said frame, means for adjusting said abrasive means with respect to the frame, a quadrant pivotally connected at one of its ends to said frame, an obliquely disposed arm fixed upon said slide bar, and means carried by said arm coöperating with the quadrant to secure said frame in its adjusted position against tilting movement with respect to the bar.

5. In a jointer for wood working machines, a base, a bar longitudinally adjust-

able upon said base, means for adjusting said bar, a frame pivotally mounted upon one end of said bar, abrasive means longitudinally movable upon said frame, means for adjusting said abrasive means with respect to the frame, a quadrant pivotally connected at one of its ends to said frame, an obliquely disposed arm fixed at one end upon said slide bar, the other end of said arm terminating in a threaded shank, said quadrant including spaced bars disposed upon opposite sides of said shank, and clamping means

engaged upon said threaded shank to clamp the quadrant bars against movement upon the end of the arm and secure said frame in 15 its adjusted position against pivotal movement with respect to the slide bar.

In testimony whereof I hereunto affix my signature in the presence of two witnesses.

JESSE W. FOSTERLING.
